BUILDING BLOCK

Lewis H. Weitz, Jr., Wampum, Pa.

Application February 10, 1950, Serial No. 143,417

2 Claims. (Cl. 20—4)

1

This invention relates to improvements in building blocks and the wall structures formed thereby, and more particularly to improved hollow building blocks formed by securing together, as by nailing or screwing together several pieces, plates, or boards of wood or other nailable composition material, the primary object of the invention being to provide hollow building blocks of this kind which are adapted to be laid and arranged like ordinary bricks or building blocks, with the improved blocks nailed together in superimposed courses of overlapping blocks, so as to form strong and durable but inexpensive wall structures.

Another important object of the invention is to provide a building block of the character indicated above involving spaced sidewalls arranged to rest upon the upper edges of similar sidewalls of subjacent blocks whereby the weight of the wall is imposed on the sidewalls rather than upon the nails or screws assembling the components of the blocks; and wherein a foreshortened top plate or wall is provided which affords spaces at the ends of the block in which a tool, such as an ordinary hammer, can be freely operated to drive nails or screws downwardly through end portions of the bottom wall or plate of the block for connecting the block to a subjacent block or to a sill.

Other important objects and advantageous features of the invention will be apparent from the following description and the accompanying drawings, wherein merely for purposes of illustration herein, a specific embodiment of the invention is set forth in details.

In the drawings:

Figure 1 is a perspective view of partially formed walls intersecting in a corner, in accordance with the present invention.

Figure 2 is a top plan view of such a wall.

Figure 3 is a vertical longitudinal section taken on the line 3—3 of Figure 2; and,

Figure 4 is a transverse vertical section taken on the line 4—4 of Figure 3.

Referring in detail to the drawings, wherein like numerals designate like parts throughout the several views, each block 5 is elongated rectangular in form and preferably but not necessarily square in cross section, and is composed of inner and outer side plates 6 and 7, respectively, and a bottom plate 8 which are similar in size, and a shorter top plate 9 having ends 10 which are spaced inwardly from the ends of the block to provide space 11 for the operation of a tool, such as a hammer, for driving nails downwardly through end portions of the bottom plate 8.

2

These plates are pieces of board or of nailable composition material, of desired thickness.

The lower edge portions of the side plates 6 and 7 are abutted with the side edges 12 of the bottom plate 8 and are secured thereto by nails or screws 13 driven through the side plates with the edges 12 at longitudinally spaced intervals, as shown in Figure 1. The upper edge portions of the side plates are abutted to the side edges of the abbreviated top plate 9 and screws 15 are driven through the side plates into the top plate edges 14. The upper and lower edges 16 and 17, respectively, of the side plates 5 and 6 are level with the upper and lower surfaces of the top plate 9 and bottom plate 8, respectively.

A wall in accordance with the present invention is formed by laying a horizontal course of blocks 5 in end to end relation, either upon a sill 18 or upon a subjacent course of blocks 5. In the latter case the blocks 5 of the upper course are staggered with respect to the blocks of the subjacent course, as shown in Figures 1 and 3, whereby upper blocks 5 straddle the conjoined ends of the lower blocks. Nails 19 are driven downwardly through end portions of the bottom plate 8 by wielding a hammer or other tool in the spaces 11, so as to connect blocks either to the sill 18 or to the top plates 9 of subjacent blocks.

In forming a corner between right angularly intersecting walls, the open ends of the final blocks 5 at the intersecting ends of the walls are closed by nailing extra plates 20 on the ends of the side and bottom walls, as indicated at 21.

What is claimed is:

1. A hollow building block comprising laterally spaced vertical side plates, a horizontal bottom plate substantially coextensive with said side plates with lower edge portions of the inner sides of said side plates secured in abutting relation to the side edges of said bottom plate, and a horizontal top plate shorter than said side plates and having ends longitudinally spaced inwardly from the ends of said side plates, upper portions of the inner sides of said side plates being secured in abutting relation to the side edges of said top plate, opposite end portions of said bottom plate being exposed at the ends of said top plate to afford nail receiving areas through which nails are adapted to be driven downwardly by a tool manipulated in the spaces provided by the spacing of the ends of said top plate from the ends of the top plate and plates.
2. A wall composed of upper and lower superimposed horizontal courses, each course consisting of a plurality of blocks arranged in end to

55

end relation with the blocks of the upper course overlapping the adjacent ends of the blocks of the lower course, each of said blocks comprising a pair of laterally spaced vertical longitudinal side plates, a bottom plate coextensive in length with the side plates and secured between the side plates at the lower edges thereof, and a top plate secured between the side plates at their upper edges, said top plate being substantially shorter than the bottom plate with the ends of the top plate longitudinally spaced from the ends of the bottom plate and exposing nailing areas at the opposite ends of said bottom plate, blocks of the upper course being laid upon and overlapping two adjacent blocks of the lower course with their bottom plates resting upon the top plates of the adjacent lower course blocks, and nails driven downwardly through the nailing areas of the bot-

tom plates of the upper course blocks into the top plates of adjacent lower course blocks.
